CLAIM

The ornamental design for a shoe, as shown and described.

DESCRIPTION

FIG. 1 is a right side view of the shoe showing my new design;

FIG. 2 is a left side view thereof;

FIG. 3 is a front view thereof;

FIG. 4 is a rear view thereof;

FIG. 5 is a top plan view thereof;

FIG. 6 is a bottom plan view thereof; and,

FIG. 7 is a top, front, and right perspective view thereof.

Any broken lines in the drawings indicate portions which form no part of the claimed design.

1 Claim, 7 Drawing Sheets# US D893,855 S
